UNITED STATES PATENT OFFICE.

FRANK P. SAWDERS AND JAMES G. MURRAY, OF PITTSBURGH, PENNSYLVANIA.

MUFFLER.

1,342,464.

Specification of Letters Patent. Patented June 8, 1920.

Application filed December 2, 1919. Serial No. 341,952.

To all whom it may concern:

Be it known that we, FRANK P. SAWDERS and JAMES G. MURRAY, citizens of the United States, residing at Pittsburgh, in the county 5 of Allegheny and State of Pennsylvania, have jointly invented a new and useful Improvement in Mufflers, of which improvement the following is a specification.

Our invention relates in particular to exhaust mufflers for the exhaust of internal 10 combustion motors as employed on automobiles, auto trucks, etc.

Our invention has for its principal objects, to provide a muffler wherein the resultant products of combustion exhausted from the motor will be thoroughly diffused and silently exhausted therefrom without occasioning back-fire. Other objects are to provide a muffler that will be durable, simple 15 in construction, not liable to get out of order, etc.

With the above objects in view, the invention consists in certain novel features of construction and arrangement of parts as 20 will hereinafter be specifically described and particularly pointed out in the appended claims.

In the accompanying drawings, forming 25 a part of this specification, we have shown one embodiment of our invention, wherein,

Figure 1 is an end elevation of said muffler and Fig. 2 a longitudinal central section through the same.

The device comprises a chambered member, formed of the cylindrical body portion 35 1 having integral heads 2 and 3, respectively. The receiving end, or head 2, has an extended centrally disposed sleeve portion 4 communicating with the interior by 40 way of the opening 5, said sleeve being divided at 6 and provided with lugs 7 having holes 7' therethrough for the reception of a suitable clamping bolt. This sleeve portion is adapted to receive the end of the exhaust 45 conduit or pipe and be clamped thereto by the bolt mentioned. Within the chamber is the primary deflector or partition 8 which extends upwardly and rearwardly at an incline 50 for a distance of about two-thirds the diameter, said inclination approximating forty five degrees. The upper portion of the discharge end 3 of the chamber, is inclined downwardly at about right angles to that of the primary deflector 8, for about 55 two-thirds the internal diameter, so as to form a secondary deflector. This secondary

deflector is somewhat contracted at its lower end, the chamber being correspondingly tapered for a short distance at each side thereof, the end of which terminates in and 60 forms the upper wall of the rectangular main discharge opening 9. This main discharge opening, presents an area in cross section, somewhat less than that of the open space of the chamber at the upper end of 65 the primary deflector as for example, about one-half area. Formed through the lower part of the chamber body is a plurality of auxiliary discharge openings 10, part of which are located toward and beneath the 70 main discharge opening, the remainder being located toward or beneath the primary deflector. For suspension of the device there is formed on the upper side of the cylindrical portion of the body, a lug 11. 75

In practice, the exhaust gases being in motion by the impulse, enter and come into contact with the primary deflector 8 by which the same is deflected upwardly toward and come into contact with the upper portion of 80 the secondary deflector. It is then deflected downwardly by this deflector toward and partially passes out of the main discharge opening 9, the remaining portion being still in motion, and in effect then tending to be 85 in something like rotary motion, partially passes out of the group of auxiliary openings 10, below the main opening, and the remainder out of the remaining auxiliary openings 10 beneath the primary deflector. 90 The complete course of the exhaust through the muffler, as set forth, is indicated by the arrows in Fig. 2.

By constructing the muffler to operate on the principle set forth, it will be readily apparent that the exhaust gases or products of combustion, will be diffused in passing therethrough to the atmosphere, and in so passing to the atmosphere will be broken up or separated, having the effect of silencing the discharge. Furthermore, the internal arrangement and operation of the exhaust in passing therethrough, is such as to be practically eliminated. 95

Having thus fully shown and described 100 our invention, what we claim, is

1. A muffler comprising a chambered member provided with an intake opening and with a plurality of spaced discharge openings of main and auxiliary order, the 110 auxiliary openings being each of less area than that of the main, and further provided

with oppositely inclined deflectors, one of said deflectors leading directly to and terminating with the main discharge.

2. A muffler comprising a chambered member provided with an intake opening and with a plurality of spaced discharge openings of main and auxiliary order, the auxiliary openings being each of less area than that of the main, and further provided, 10 with primary and secondary deflectors disposed at approximately right angles to one another, one of said deflectors leading directly to and terminating with the main discharge.
- 15 3. A muffler comprising a chambered member having a head at its forward end which is provided with an intake opening and at its rear with a head disposed at an inclination to form a secondary deflector 20 and terminating in an elongated main discharge opening, said chamber having a primary deflector formed therein at approximately right angles to said secondary deflector, said member being further provided 25 with a plurality of auxiliary discharge open-

ings disposed in the lower rearward portion thereof between the main discharge and primary deflector.

4. A muffler comprising a chambered member having a head at its forward end which is provided with an intake opening and at its rear with a head having an inclined portion forming a secondary deflector which terminates with a transversely disposed main discharge opening formed in 30 said head, said chamber having a primary deflector formed therein at approximately right angles to said secondary deflector, said member being further provided with a plurality of auxiliary discharge openings 35 disposed in the lower rearward portion of the chamber and head.

In testimony whereof we have hereunto signed our names in the presence of two subscribing witnesses.

FRANK P. SAWDERS.
JAMES G. MURRAY.
